METAL STRUCTURE

Franco Mazzini, Milan, Italy, assignor to Societa Italiana Ernesto Breda per Costruzioni Mecaniche, Milan, Italy

Application May 15, 1933, Serial No. 671,229
In Italy June 18, 1932

6 Claims. (Cl. 189—34)

This invention relates to reinforced skin plating and other constructional parts of air and water craft.

I have previously proposed in my British Patent, No. 387,869, complete accepted February 16, 1933, to form constructional parts for the building of aeroplanes and the like of thin plates strengthened by raised parts or bosses produced by local stamping and arranged in parallel rows, 10 if necessary staggered with respect to each other, so that the raised parts of each row are interposed between those of the two lateral rows. This arrangement strengthens the plates in a direction parallel to the rows of raised parts while 13 permitting their adaptation to curves in a transverse direction.

It is, however, sometimes necessary for the plates to be adjusted to multiple and complicated curves in various directions, while being fully 20 strengthened in other directions. It is theoretically possible to vary as desired the distribution of the raised parts so as to obtain in each zone of the plates the degree and character of strengthening necessary; nevertheless it must be recognized 25 that this system is not convenient from the practical point of view of convenient construction. This invention has for its object an arrangement which not only renders the manufacture very simple but it permits of an absolute 30 strengthening in zones having any shape, extent and position, while leaving the other zones of the strengthened plates adaptable to any necessary curve in any direction whatever.

The invention resides in the main plating of a 35 structure or constructional part, strengthened by means of rows of elongated bosses or raised parts as aforesaid being reinforced by similarly strengthened reinforcing plating and fixed in any manner and in any desired location to the 40 main plating such that their bosses are aligned in rows at any angle, or non parallel to the rows of bosses in the main plating.

Ordinarily the pieces of reinforcing plating 45 may take the shape of rectangular or parallelogram shaped bands, but they may also be of any other shape. They may be arranged parallel to each other or lie at any angle to one another, they may be fitted at right angles to the rows of bosses of the main plating or at any inclination 50 thereto. They may be fixed by riveting, bolting or by welding, preferably autogenous.

In order to more clearly show the nature and extent of the invention, there are shown on the annexed drawing several simplified methods of 55 execution, given as examples in which:—

Fig. 1 is a transverse sectional view of a construction plate according to the present invention.

Fig. 2 is a fragmentary elevational view of the construction plate.

Fig. 3 is a sectional view taken on line 3—3 of Fig. 2.

Fig. 4 is a view similar to Fig. 2 illustrating a modified form of the invention.

Fig. 5 is a sectional view taken on line 5—5 of Fig. 4.

Fig. 6 is another view similar to Fig. 2 illustrating a still further modified form of the invention, and

Fig. 7 is a sectional view taken on line 7—7 of Fig. 6.

Referring to the drawing in each of the embodiments shown metal plates 1 which are strengthened by rows of bosses 2—3 are reinforced by bands 4—5 which, in their turn, are 20 strengthened by rows of bosses 6—7 and 8—9 which are aligned in a direction at an angle, that is, non-parallel, to the alignment of the bosses 2—3 strengthening the plates 1. It is evident that reinforced zones produced by the strengthened bands 4—5 applied by riveting, bolting or welding, are created extending in any direction owing to the effect of the non-parallel arrangement of the bosses 2—3 of the plates 1 and the bosses 6—7 and 8—9 of the reinforcing bands 30 4—5.

By suitably choosing the shape, width and position of the pieces 4—5, it is possible and easy to strengthen zones of any shape and extent in the plates of the structure.

As clearly shown in Figs. 3, 5 and 7, main plate 1 is provided with flanges 10 and 11 which serve as a means of attaching the plates together. These figures also illustrate the flanges 12 and 13 which cooperate with the flanges 10 and 11. 40 Rivets 14 or equivalent securing means cooperate with the flanges of the main plates and reinforcing strips and serve for connecting the main plates together and the reinforcing strips to the main plates.

What I claim is:

1. Reinforced constructional element of metal plate comprising a main plate strengthened by locally stamped elongated bosses arranged in parallel rows, said main plate having side flanges, a plurality of strips of reinforcing plates associated with the main plate and provided with rows of strengthening bosses at an angle to the rows of bosses of the main plate, said strips having flanges cooperating with those of the main 50 55 plate.

- plate, and means securing the flanges of the strips to the flanges of the main plate.
2. Reinforced skin plating for air and water craft comprising main skin plating strengthened by locally stamped elongated bosses arranged in parallel rows, said main plating having side flanges, a plurality of strips of reinforcing plating associated with the main plating and provided with rows of strengthening bosses at an angle to the rows of bosses of the main plating, said strips having flanges cooperating with those of the main plating, and means securing the flanges of the strips to the flanges of the main plating.
3. Reinforced constructional element of metal plate comprising a main plate strengthened by locally stamped elongated bosses arranged in parallel rows, said main plate having side flanges, a plurality of strips of reinforcing plates associated with the main plate and provided with rows of strengthening bosses at right angles to the rows of bosses of the main plate, said strips having flanges cooperating with those of the main plate, and means securing the flanges of the strips to the flanges of the main plate.
4. Reinforced skin plating for air and water craft comprising main skin plating strengthened by locally stamped elongated bosses arranged in parallel rows, said main plating having side flanges, a plurality of strips of reinforcing plating associated with the main plating and provided with rows of strengthening bosses at right angles to the rows of bosses of the main plating, said strips having flanges cooperating with those of the main plating, and means securing the flanges of the strips to the flanges of the main plating.
5. Reinforced skin plating for air and water craft comprising main skin plating strengthened by locally stamped elongated bosses arranged in parallel rows, said main plating having side flanges, a plurality of strips of reinforcing plates associated with the main plating and provided with rows of strengthening bosses in each strip parallel to each other and at an angle to the rows of bosses of the main plating, said strips having flanges cooperating with those of the main plating, and means securing the flanges of the strips to the flanges of the main plating.
6. Reinforced skin plating for air and water craft comprising main skin plating strengthened by locally stamped elongated bosses arranged in parallel rows, said main plating having side flanges, a plurality of strips of reinforcing plating associated with the main plating and provided with rows of strengthening bosses, the rows of bosses on one strip being at an angle to the rows of bosses on another strip and the rows on both of said strips at an angle to the rows on the main plating, said strips having flanges cooperating with those of the main plating, and means securing the flanges of the strips to the flanges of the main plating.

FRANCO MAZZINI.
